APPARATUS FOR PRACTICING FOOTBALL
GOAL KICKING

Robert E. Whalen Perry, Los Angeles, Calif.

Substituted for abandoned application Serial No.
457,303, September 4, 1942. This application
July 22, 1944, Serial No. 546,070

7 Claims. (Cl. 35—29)

This invention is an apparatus for practicing football goal kicking, and this application is a substitute for my abandoned application, Serial No. 457,303, filed September 4, 1942, for Apparatus for practicing football goal kicking.

The general object of the invention is to provide an apparatus with a football arranged to be picked straight ahead toward a simulated goal or to either side of said simulated goal.

Another object is to provide an apparatus for practicing football goal kicking with means for indicating the force with which the football is kicked.

Other objects and advantages will appear hereinafter.

The invention is illustrated in the annexed drawings which form a part of this specification and in which

Fig. 1 is a side elevation of my invention.

Fig. 2 is a front elevation of my invention.

Fig. 3 is a vertical longitudinal section taken on line 3—3 of Fig. 4 illustrating the rock shaft and the swivel joint connecting the football arm to said shaft.

Fig. 4 is a transvertical section of Fig. 3 taken on line 4—4 of Fig. 3.

Fig. 5 is a vertical section of coin-controlling mechanism and kick indicator taken on line 5—5 of Fig. 6.

Fig. 6 is a vertical section of Fig. 5 taken on line 6—6 of Fig. 5.

Fig. 7 is a view of the pawl and ratchet which locks the apparatus in inoperative position.

Fig. 8 is a front elevation of a modification of my invention.

Fig. 9 is a side elevation of Fig. 8 with the target in position to be struck by the football when kicked.

Fig. 10 is a side elevation of Fig. 8 showing the football kicked against the lowermost target slat and said slat and the remaining slats of the target turned on their pivots, and showing the uppermost slat turned so that its rear side is exposed at the front of the target.

Referring more particularly to the drawings in which corresponding parts are designated by the same reference characters in all of the figures, 1 designates a floor base and 2 designates a vertical wall upstanding from said floor base near the rear thereof, said vertical wall being braced at its rear side by angle braces 3 secured at their lower ends to the floor base 1 rearwardly of said wall, and at their upper ends to the rear side of said wall. The upper edge 4 of the wall 2 is

arcuate, and along said edge is arranged a football target 5 comprising a plurality of target plates 6, 7 and 8, hinged respectively by spring hinges 9 at their lower edges to said upper edge 4 of said wall 2, at the rear of said plates and said wall, the plate 6 being located centrally between the side edges of the wall 2 and between the innermost target plates 7 and 8. The target plate 6 indicates a football goal, while the target plates 7 and 8 indicate distances, respectively and progressively, from the left and from the right of said goal. The spring hinges 9 normally hold the target plates 6, 7 and 8 in a vertical position, but allow said plates to swing backwardly, 10 when struck in front by a football 10, as illustrated in dotted lines in Fig. 1 of the drawings. A horizontal rock shaft 11 is journaled in ball bearings 12, 13 and 14 a short distance above the floor base 1 and a short distance forwardly of the wall 2, parallel to said wall, which ball bearings are secured in mountings 15, 16 and 17, the mountings 15 and 16 being supported upon and secured to the floor base 1, and the mountings 17 being supported upon and secured to the lower 15 wall of a casing 18 within said casing, which casing rests upon and is secured to the floor base 1, for the purpose hereinafter more fully described. An arm 19 is connected at its rear end to the rock shaft 11 between the bearings 12 and 20 13 by means of a swivel joint 20, and on the forward end of said arm is secured the football 10. The swivel joint 20 comprises a spherical hub 21 and a yoke 22 surrounding said hub, which hub is secured on the rock shaft 11 between the bearings 12 and 13, and the rear end of the arm 19 is secured to said yoke, there being external ribs 23 on the hub 21 and transverse grooves 24 in the inner side of said yoke, in which grooves are slidably fitted said ribs 23, whereby said yoke is 25 allowed to swing either to the right or to the left on said spherical hub 21. A coil spring 25 surrounds the rock shaft 11, with one end of said spring engaging a lug 26 on the bearing mounting 16, and the other end of said spring engaging 30 a collar 27 secured on said rock shaft, which spring, with predetermined force, resists turning movement of the rock shaft 11 by upward rearward movement of the arm 19, when the football 10 is kicked rearwardly and upwardly, and said spring turns said rock shaft 11 and swings said arm 19 and football 10 down, until said football rests upon the floor base 1, each time said football is kicked, as aforesaid, so that said arm 35 and said football are normally maintained, by 40 50

the spring 25, in their lowermost position, with the football resting upon the floor base 1 in position to be kicked, as illustrated in Fig. 1 of the drawings.

As indicator 30 is provided to indicate the force with which the football 10 is kicked, which indicator includes a scale 31, an indicator bar 32 movable over said scale, a rack 33 on said indicator bar, a gear 34 in mesh with said rack, a shaft 35 on which said gear is secured, a pinion 36 on said shaft 35, and a gear 37, on rock shaft 11, in mesh with said pinion. The bar 32, rack 33, gear 34, shaft 35, pinion 36, and gear 37 are enclosed in the casing 18. The upper end portion of the indicator bar 32 extends through and is slidably fitted in a slot 38 in the upper wall 39 of the casing 18, while the rear side of said bar, opposite the rack 33, slidably rests against a straight bearing 40 on the inner side of the rear wall of the casing 18. The shaft 35 is journaled in ball bearings 41 and 42, the bearing 41 being secured in the bearing mounting 17, and the bearing 42 being secured in a bearing mounting 43 which is secured to the lower wall of the casing 18 within said casing.

My apparatus may be controlled by a coin-control mechanism 50, which locks the apparatus against operation until said mechanism is actuated upon depositing a coin therein of a predetermined denomination. Said coin-control mechanism includes a ratchet 51, secured on the shaft 35 between the bearing mountings 17 and 43, a pawl 52, for engaging said ratchet, pivoted at 53 on the upper part 43 of bearing mounting 43, a spring plunger rod 54 for engaging, at its lower end, one end of said pawl 52, a coin-actuating spring plunger 55 for actuating said spring plunger rod, a coin-receiving chute 56 for said coin-actuating spring plunger, and a coin-collecting drawer 57 for receiving and collecting coins deposited in said coin chute 56, after said coins have been received in and acted upon by said coin-actuating spring plunger 55 in depressing said spring plunger rod 54, whereby the lower end of said rod is caused to engage and swing the pawl 52 out of engagement with the ratchet 51 to release my apparatus for operation in the manner hereinafter more fully described. The spring plunger rod 54 is slidably mounted in bearings 58 and 59 extending inwardly from the front wall of the casing 18 within said casing, and a coil spring 60 surrounds said plunger rod 54 with the lower end of said spring resting against the bearing 58 and the upper end of said spring bearing against a collar 61 secured on said plunger rod, whereby said plunger rod is normally held in its elevated position with its lower end releasing the pawl 52 and allowing said pawl to swing into engagement with the ratchet 51 and lock the apparatus against operation. The coin-actuating spring plunger 55 is bored upwardly longitudinally from its lower end as indicated at 62, to receive loosely the upper end portion of the spring plunger rod 54, and said coin-actuating spring plunger is provided with coin slots 63 and 64 arranged diametrically opposite each other with the slot 64 a short distance below the slot 63, the slot 63 registering with the lower inner end of the coin chute 56 when the plunger 55 is in its uppermost position, as illustrated in Figs. 5 and 6 of the drawings. Said plunger 55 is slidably mounted in a bearing 65 secured in the upper forward part of the casing 18, through the forward wall of which bearing extends the lower

inner end of the coin chute 56. Said bearing 65 is provided with a coin-outlet slot 66 located below the lower inner end of the coin chute 56. From the upper end of the coin-actuated plunger 55 extends a plunger stem 67 upwardly through an opening 68 in the upper wall of the casing 18 and a knob 69 is secured on the upper end of said stem, there being a coil spring 70 surrounding said stem 67 between the upper wall of said casing 18 and said knob 69 which spring normally holds said plunger 55 in its uppermost position, with the coin slot 63 in registration with the lower inner end of the coin chute 56. The coin-collecting drawer 57 is slidably mounted in a frame 71 in the casing 18 immediately below the coin outlet slot 66, and extends through a side wall of said casing, so that the drawer may be withdrawn from time to time to collect the coins dropped therein from the plunger 55, through the outlet slot 66, after the coins have been introduced into and have been acted upon by said plunger when depressed, for unlocking the apparatus for operation, in the manner hereinafter more fully described.

The operation, uses and advantages of my invention are as follows:

Normally the arm 19 and football 10 are locked in their uppermost position, as shown in dotted lines in Fig. 1 of the drawings, by the engagement of the pawl 52 with the ratchet 51, and the coin-actuating spring plunger 55 and spring plunger rod 54 are held in their uppermost positions by their springs 70 and 60, respectively, while the indicator bar 32 is held in an elevated position by the engagement of the gear 34 with the rack 33.

When a football player desires to practice a football goal kick with my apparatus he first deposits a coin 75 of the proper denomination in the coin chute 56, which coin rolls down said chute into the slots 63 and 64 in the coin-actuating plunger 55, with the lower edge of said coin resting immediately above the upper end of the spring plunger rod 54. The football player then places his thumb on the knob 69 and depresses the coin-actuating plunger 55, whereupon the lower edge of the coin 75, engaging the upper end of the spring plunger rod 54, causes said rod to be depressed against the tension of the spring 60 and the lower end of said rod 54 to engage the forward end of the pawl 52 and swing said pawl out of engagement with the ratchet 51 and unlock the apparatus, whereupon the arm 19 and football 10 swing down under the influence of the spring 25 actuating the rock shaft 11 and swivel joint 20, until the football rests upon the floor base 1, while the indicator bar 32 is lowered by the turning rock shaft 11, through the medium of the gear 37, pinion 36, shaft 35, gear 34 and rack 33, until the upper end of said indicator bar 32 coincides with the zero graduation on the scale 31 of the indicator 30, as shown in Figs. 5 and 6 of the drawings. The football player then releases the knob 69, whereupon the coin 75 rolls out of the coin-control plunger 55 through its slot 64 and then rolls through the slot 66, in bearing 65, into the cash drawer 57, and said plunger 55 is elevated by its spring 70 to its normal uppermost position, while the plunger rod 54 is elevated to its normal uppermost position by its spring 60, and the pawl 52, being released by the elevation of the lower end of said plunger rod 54 swings back into the ratchet 51. The football player then kicks the foot-

ball 10 toward the goal represented by the goal plate 6 of the target 5, whereupon the football and arm 19 are swung upwardly and rearwardly, straight ahead, or to one side or the other, on the swivel joint 20 against the tension of the spring 25, until the football strikes either the goal plate 6 or one of the target plates 7 or 8 at the left or right of said goal plate, and the plate struck by the football is thereby swung backwardly on its hinge 9, as shown in dotted lines in Fig. 1 of the drawings, thus indicating on the target 5 the position to which the football is kicked, and more particularly indicating whether the football has been kicked to the goal, or how far to the left or to the right of the goal the football has been kicked.

As the football 10, upon being kicked, is swung upwardly and forwardly as above described, the rock shaft 11 and gear 37 are correspondingly turned, and said gear turns the pinion 36, shaft 35, ratchet 51 and gear 34, the pawl 52 escaping said ratchet, and the gear 34 in mesh with rack 33 elevates the indicator bar 32, until the force of the kick of the football is spent and the football 10 and arm 19 reach the end of their upward and forward swinging movement and the indicator bar 32 reaches the end of its upward movement, in which position the football 10, arm 19 and indicator bar 32 are arrested and locked against backward movement by the engagement of the pawl 52 with the ratchet 51, and the upper end of said indicator bar 32, coinciding with a graduation of the scale 31 of the indicator 30, indicates the force of the kick of the football. The target plate 6, 7 or 8, which was struck by the football, when kicked, and swung forwardly thereby, is swung back to its normal vertical position by its spring hinge 9, as shown in full lines in Fig. 1 of the drawings.

My apparatus cannot be unlocked for operation without depositing a proper coin in the coin chute 56, because, without a coin in this coin-actuating spring plunger 55 to engage the upper end of the spring plunger 54, the plunger 55 may be depressed without depressing the spring plunger 54, the bore 62 of the plunger 55 extending upwardly far enough to receive the upper end portion of the spring plunger rod 54 upon depressing the plunger 55.

In the modification of my invention, shown in Figs. 8, 9 and 10 of the drawings, the mechanism is the same as that shown in Figs. 1 to 7 inclusive, with the exception that a football target 50 is substituted for the football target 5. The target 50 comprises an inverted U-shaped frame 81 upstanding from the rear part of the floor base 1, a plurality of superimposed horizontal target slats 82, 83, 84, 85, 86 and 87 pivoted respectively at their ends, by pivots 88, 89, 90, 91, 92 and 93, in the upper portion of the upright members 94 of said frame 81, and a basket 95 mounted on the rear side of said upright members 94 behind the lowermost slat 82 to receive the football 10 when kicked to one side by a player of my football goal-kicking apparatus. The lowermost slat 82 is formed in its lower edge with two large indentations 96 and 97 and with a depending tongue 98 between said indentations located centrally of the target 50. From the upper rear edge of the lowermost target slat 82 extend a pair of suitably spaced lugs 99 for extending upwardly over the rear lower rear edge of the slat 83 and engaging the rear side of said slat when said slats are in vertical alignment. From the upper front edge of the

slat 83 extend a pair of suitably-spaced lugs 100 for extending upwardly over the lower front edge of the slat 84 when said slats are in vertical alignment. From the upper rear edge of the slat 84 extend a pair of suitably-spaced lugs 101 for extending upwardly over the lower rear edge of the slat 85 when said slats are in vertical alignment. From the upper front edge of the slat 85 extend a pair of suitably-spaced lugs 102 for extending upwardly over the lower front edge of the slat 86, when said slats are in vertical alignment. From the upper rear edge of the slat 86 extend a pair of suitably-spaced lugs 103 for extending upwardly over the lower rear edge of the uppermost slat 87, when said slats are in vertical alignment.

On the rear side of the uppermost slat 87 is painted or otherwise represented a football, as indicated at 104. On the front side of the slats 83, 84, 85 and 86 are painted or otherwise represented for decorative purposes a suitable picture such as the picture of football players on a football field.

The operation of the modification of my invention as shown in Figs. 8, 9 and 10 is as follows:

When the football 10 is kicked by a player the football and arm 19 will swing upwardly and forwardly on the swivel joint 20, and if the football is kicked straight and hard enough it will strike the depending tongue 98 of the lowermost slat 82 and swing said slat counter-clockwise (Figs. 9 and 10) on its pivots 88 and the lugs 99 on said slat will engage the rear side of the slat 83 below its pivots 89 and swing said slat 83 clockwise on its said pivots 89; the lugs 100 on the slat 83 will engage the front side of the slat 84 below its pivots 90 and swing said slat 84 counter-clockwise on its said pivots 90; the lugs 101 on the slat 84 will engage the rear side of the slat 85 below its pivots 91 and swing said slat 85 clockwise on its said pivots; the lugs 102 on the slat 85 will engage the front side of the slat 86 below its pivots 92 and swing said slat 86 counter-clockwise on its said pivots; and the lugs 103 on the slat 86 will engage the rear side of the uppermost slat 87 below its pivots 93 and swing said slat 87 clockwise on its pivots 93 one half revolution bringing the rear side of the slat 87 to the front of the target 50 and exposing the picture 104 of a football on the rear side of said slat 87 and thereby indicating that a goal has been kicked by the football player kicking the football 10.

If the football 10 is kicked straight ahead, but not hard enough to be kicked to a goal, the football will strike the depending tongue 98 on the lowermost slat 82 and will turn said slat counter-clockwise, and the remaining slats 83, 84, 85, 86 and 87 will be successively turned, in the manner hereinabove described, but not sufficiently to turn the uppermost slat 87 a half-revolution to expose the representation of a football 10 on said slat to the front of the target 50, thus failing to indicate that a goal has been kicked and thereby indicating that a goal has not been kicked.

If the football 10 is kicked to the left or to the right the arm 19 will be correspondingly swung to the left or to the right on the swivel joint 20, and the football will escape the tongue 98 and swing through the indentation 96 or 97 in the lower edge of the lowermost slat 82, into the basket 95, as shown in Fig. 9 of the drawings, and the target 50 will thereby be missed by the

football and will fail to expose the representation of the football 104 to indicate a good kick, while the position of the football in the basket 95 to the left, or to the right of the tongue 98 will indicate that the football was kicked either to the left or to the right of a goal.

My invention may be used as a game.

I claim:

1. An apparatus for practicing football goal kicking including a goal, a football, and means for mechanically controlling the trajectory of said football towards said goal or to one side or the other of said goal, according to the direction in which said football is kicked.

2. An apparatus for practicing football kicking including a shaft suitably journaled, an arm, a football secured on one end of said arm, and swivel means for connecting the other end of said arm to said shaft whereby said football when kicked may swing upwardly in a vertical plane or to one side or the other of said plane.

3. An apparatus as claimed in claim 2 including a pawl and ratchet arranged to arrest the football in an elevated position to which the football is swung when kicked, and means for disengaging said pawl from said ratchet to permit the football to swing down into position to be kicked.

4. An apparatus for practicing football goal kicking including a target constructed and ar-

ranged with a plurality of pivoted slats located one above another and interengaging means on said slats, a football, and means for mounting said football to be kicked against said lowermost slat to turn said slat on its pivots and to cause said slat, by said interengaging means, to turn said remaining slats on their pivots.

5. An apparatus for practicing football goal kicking including a target constructed and arranged with a plurality of pivoted slats located one above another and interengaging means on said slats, the lowermost slat being formed with a depending tongue, a football, and means for mounting said football to be kicked upwardly straight against said tongue or to either side of said tongue, so that when said football strikes said tongue said lowermost slat will be turned on its pivots and cause said remaining slats to be turned on their pivots by said interengaging means.

10 6. An apparatus as claimed in claim 1 including means for automatically locking the football in an elevated position to which it is kicked, and means for unlocking said locking means to permit the football to return to its kicking position.

15 7. An apparatus as claimed in claim 1 including means for indicating the force with which the football is kicked.

ROBERT E. WHALEN PERRY.
